BOOK OR BINDER COVER

Clarence D. Trussell, Poughkeepsie, N. Y., assignor to Trussell Manufacturing Company, Poughkeepsie, N. Y., a corporation of New York

Application April 6, 1939, Serial No. 266,317

2 Claims. (Cl. 281—37)

The invention herein disclosed relates to covers for books or binders, particularly of the type covered in the Trussell Patent 1,887,530 of November 15, 1932.

5 Special objects of the present invention are to improve covers of the type identified, particularly by stiffening and reinforcing the same, to enable them to withstand more or less rough usage, even though constructed of relatively thin 10 material and to add decorative value and a sense of substantiality and permanence.

Other desirable objects and the novel features by which the purposes of the invention are attained will appear in the course of the following 15 specification.

The drawing accompanying and forming part 20 of the specification illustrates one practical commercial embodiment of the invention. The structure however may be modified and changed as regards this disclosure all within the true intent and scope of the invention as hereinafter defined and claimed.

Fig. 1 is a perspective view of a book or binder 25 having the cover of this invention applied thereto.

Fig. 2 is an enlarged plan view of the cover.

Figs. 3 and 4 are further enlarged broken sectional detail views as on lines 3—3 and 4—4 respectively of Fig. 2.

30 The cover shown consists of a single sheet of fairly stiff material, folded about the binder or book structure 5, to form the covers 6, and back 7.

The covers have inwardly curved or rolled marginal portions 8, extending continuously from or 35 near the back, to and around the corners of the book.

A special feature of the present invention is the provision of the inwardly rounded marginal 40 portions of the cover with longitudinal and transverse embossments such as indicated at 9, 10, 11.

The longitudinal embossments 9, form a ridge or rib substantially parallel with the edge of the 45 cover and located substantially at the merger of the curved marginal portion into the substantially flat main body portion of the cover.

The transverse embossments 10, are shown as 50 forming short curved ribs or ridges extending between the marginal edges 12, Fig. 3, and the longitudinal ridges 9.

The other set of transverse embossments 11, are shown as extending from near the edges 12, 55 Fig. 4, back through the curved marginal edge

portion and through the longitudinal ridges 9, into the main flat body portion of the cover.

The longitudinal ridge 10, is shown interrupted at points 13, and at these points, transverse ridges 14, are shown extending from the curved 5 marginal portion back beyond the interrupted portions of the longitudinal ridge into the flat main body portion of the cover.

At the corners diagonally extending ridges are shown at 15, extending from the curved marginal 10 portion back between interrupted corner portions of the longitudinal ridge at 16, into the flat main body portion of the cover. These diagonal corner ridges are shown as terminating between the ends of adjoining transverse ridges 14. The 15 two transverse ridges 14 and intervening diagonal ridge 15, constitute cooperative corner bracing elements.

Instead of a single diagonal brace 15, at each 20 corner, any number of such bracing elements may be provided, arranged in fanwise disposition.

Various materials may be used for the covers, 25 preferably such however that may be readily molded and pressed in the manner indicated. The present invention makes it possible to use relatively inexpensive materials, such as a sheet material of a paper base impregnated with latex while the pulp is in the liquid state. This material is readily molded and, when embossed as 30 illustrated, will hold the desired marginal curvature. The embossments give the curved marginal portion a desirable springy quality, enabling it to yield and to spring back into its 35 original shape. The combination of longitudinal and transverse ridges braces the cover in all directions and gives it a sense of thickness and 35 substantiality, materially enhancing the appearance and feel of the cover as well as actually increasing its durability.

40 What is claimed is:

1. A book cover, comprising a single sheet of thin, flat, flexible material with straight edges joined by rounded corners, the marginal edge 45 portions of said thin, flat, flexible sheet material being inwardly curved transversely of the sheet and continuously along said straight edges and about said rounded corners in a permanently arched condition and a narrow longitudinal ridge outwardly embossed transversely of the sheet and 50 extending substantially parallel with the edges and about the corners at approximately the junction of the curved marginal edge portions with the main body of the flat sheet material and said inwardly arched marginal portion and 55

outwardly embossed ridge cooperatively reinforcing each other and jointly forming a relatively stiff frame surrounding, protecting and reinforcing the intermediate area of the sheet material within the outlines of said thus formed frame.

2. A book cover, comprising a single sheet of thin, flat, flexible material with straight edges joined by rounded corners, the marginal edge portions of said thin, flat, flexible sheet material being inwardly curved transversely of the sheet and continuously along said straight edges and about said rounded corners in a permanently arched condition, a narrow longitudinal ridge outwardly embossed transversely of the sheet and extending substantially parallel with the edges and about the corners at approximately the

junction of the curved marginal edge portions with the main body of the flat sheet material and said inwardly arched marginal portion and outwardly embossed ridge cooperatively reinforcing each other and jointly forming a relatively stiff frame surrounding, protecting and reinforcing the intermediate area of the sheet material within the outlines of said thus formed frame and additional outwardly embossed narrow ridges at the corner portions of said sheet material extending from said longitudinal ridge outwardly along the inwardly curved rim portion of the sheet material and forming hollow arched trusses between said longitudinal ridge and the edge of the sheet.

CLARENCE D. TRUSSELL.
